United States Patent Office

Des. 187,589
Patented Apr. 5, 1960

187,589

KNIFE OR SIMILAR ARTICLE

John A. Prip, Raynham, Mass., assignor to Reed and Barton Corporation, Taunton, Mass., a corporation of Massachusetts

Application November 30, 1959, Serial No. 58,506

Term of patent 14 years

(Cl. D22—3)

Fig. 1 is a top plan view of a knife embodying my new design;

Fig. 2 is a side elevational view of said knife;

Fig. 3 is a front elevational view of said knife;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 1; and

Fig. 7 is a cross-sectional view taken on line 7—7 of Fig. 1.

I claim:

The ornamental design for a knife or similar article, as shown.
